(57) **CLAIM**

The ornamental design for a doll cabinet, as shown and described.

DESCRIPTION

FIG. 1 is a perspective view of a doll cabinet showing my new design.

FIG. 2 is a front view thereof.

FIG. 3 is a right side view thereof.

FIG. 4 is a front view thereof shown with the doors open; and,

FIG. 5 is a right side sectional view thereof shown with the doors open and one drawer pulled out.

The broken line showing of hardware is for illustrative purposes only and forms no part of the claim.
